ABSTRACT

Load driver circuit (10) has first and second comparators (C₁, C₂) which receive a load current signal (V_L) indicative of current flowing through a load (11). The comparators provide, as output signals, set on and set off signals (at 21, 23) in response to comparing the load current signal (V_L) with first and second thresholds (T₁, T₂). Driver circuitry (27, 43, 12) receives the set on and set off signals and provides a current control signal (at 18) for controlling load current. Preferably, disabling circuitry (30-34) disables the comparators (C₁, C₂) after and in response to the comparators providing their respective output signals (at 21, 23). Also, preferably enabling circuitry (40-42) enables the comparators (C₁, C₂) in response to comparing a sensed voltage (at 17), indicative of voltage at an output terminal of a switching device (12) that controls load current, with respect to a predetermined voltage (2.5 volts). The selective enabling/disabling of the Comparators (C₁, C₂) results in minimizing the possible effect of noise with respect to controlling load current since undesired false or repetitive outputs of the comparators are minimized.

FIG. 1

FIG. 2

FIG. 3

LOAD DRIVER CIRCUIT

FIELD OF THE INVENTION

The present invention relates to the field of load driver circuits in which circuitry is utilized to control the current through a load. More particularly, a load driver circuit is provided which can be utilized to maintain a desired average load current in a load by alternately turning on and off a driver stage which controls the current in the load.

BACKGROUND OF THE INVENTION

Many times it is desired to control the average current through an electrical load so as to ensure the proper operation of the electrical load. For electrical loads such as the inductance coil of a solenoid relay, many prior circuits have controlled average current through the solenoid inductance by alternately turning on and off a switching device connected in series with the solenoid inductance. This preferred technique minimizes power dissipation by avoiding operating the control device in a linear mode since the control device is operated in a switching mode. Typically, the current through the solenoid inductance is sensed and the switching device is turned on when the solenoid current is below a certain level and turned off when the solenoid current exceeds a certain level. In this manner, the solenoid current will oscillate repetitively between maximum and minimum levels and thereby a desired average current level is achieved. Examples of such prior art solenoid current control systems are shown in U.S. Pat. Nos. 4,764,840, 4,300,508, 4,729,056, 4,736,267, and 4,680,667. Some of these prior systems utilize separate high and low current threshold comparators to accurately control the maximum and minimum load current levels.

Prior high and low comparator systems, such as those noted above, are subject to generating undesired or false turn-on and turn-off signals which are coupled to the switching device. This is because of noise which corrupts a load current sense signal provided to the high and low current threshold comparators. Thus, undesired or false switching of the switching device or the circuitry which generates the current control signal provided to the switching device can occur. This can disrupt the maintaining of a desired average current in the solenoid inductance.

SUMMARY OF THE INVENTION

An embodiment for a load driver circuit is described herein which comprises: first comparator for receiving a load current signal indicative of current flowing through a load and for providing as an output signal a set on signal in response to the load current signal being less than a first threshold; second comparator for receiving the load current signal and providing as an output signal a set off signal in response to the load current exceeding a second threshold more than the first threshold; and driver means coupled to the first and second comparators for receiving the set on and set off signals and providing a load current control signal for controlling current flow through the load in response thereto.

According to one aspect of the present invention there is provided a disabling means for disabling at least one of the first and second comparators in response to and after the one comparator provides its output signal.

A similar disabling apparatus may also be provided for the other one of the first and second comparators. Preferably the first and second comparators are maintained in their disabled state by the disabling apparatus until the next time occurrence of a set off or set on signal by the comparator which is not disabled. In this manner the generation of false or repetitive set on or set off signals due to noise signals is minimized.

According to another aspect of the present invention, enabling means is provided for the first and second comparators which enables at least one comparator in response to comparing a sensed voltage, indicative of the voltage at one output terminal of an output switching device that controls current in the load, with respect to a predetermined voltage. Preferably each of the comparators is alternately enabled by the enabling means. In this manner the first and second comparators are selectively enabled when the sensed voltage indicates that the first or second comparators may have to respond to the load current signal by providing their respective set on or set off signals.

According to either of the above aspects of the present invention, or their combination, an improved load driver circuit is provided in which the likelihood of creating false outputs from the first or second comparators is minimized because these comparators are either disabled at times when they are not expected to produce an output and/or because they are only selectively enabled at times when they are expected to produce an output in response to the monitored load current signal. This substantially minimizes the potential for false or erroneous operation of the load driver circuit.

BRIEF DESCRIPTION OF THE DRAWINGS

The present invention can be better understood by reference to the drawings in which:

FIG. 1 is an electrical schematic block diagram of a load driver circuit constructed in accordance with the present invention;

FIG. 2 is a graph of a voltage waveform which indicates the general operation of the load driver circuit shown in FIG. 1; and

FIG. 3 is a detailed electrical schematic of some of the components shown in block form in FIG. 1.

DESCRIPTION OF THE PREFERRED EMBODIMENTS

Referring to FIG. 1, a load driver circuit 10 is illustrated in which the load current I_L through a desired load, comprising an inductive solenoid coil 11, is controlled by the repetitive switching on and off of an output switching device 12, comprising an FET transistor, connected in series with the solenoid coil 11. One end of the solenoid coil 11 is connected to a power supply terminal 14 at which a voltage potential $B+$ is provided. The other end of the solenoid coil 11 is connected to a positive sense terminal 15. A sensing resistor R_s , also referred to herein as resistor 16, is provided between the positive sense terminal 15 and a negative sense terminal 17 which is directly connected to a drain electrode D of the FET transistor 12. The transistor 12 has a source electrode S directly connected to ground and a control input electrode G, corresponding to the gate electrode of the transistor, connected to a control input terminal 18. A flyback or recirculation diode 19 is connected between the $B+$ terminal 14 and the negative sense terminal 17 in conventional fashion.

Essentially, in response to high or low logic states provided at the control input terminal 18, the transistor 12 is switched on or off and this controls the load current I_L in the solenoid coil 11. The magnitude of this load current is sensed by a load current signal corresponding to a differential sense voltage V_s that is developed across the sensing resistor 16. The magnitude of the signal V_s varies directly in accordance with the magnitude of the load current through coil 11. The differential sense voltage V_s will be provided to two separate comparators that will determine a switching current control input signal to be provided at the terminal 18.

Referring now to FIG. 2, the overall operation of the load driver circuit 10 will be briefly explained. FIG. 2 is a graph of the sense voltage V_s versus time after a steady state condition has been achieved during which a desired average load current is provided. For values of the sense voltage V_s below a threshold T_2 , corresponding to a maximum load current threshold level, the transistor 12 is maintained in a fully conductive state. This results in the ramping up or increasing of load current through the load inductance coil 11. The current through the coil 11 cannot increase instantaneously and this is the reason for the ramping up of the current sense signal V_s as shown in FIG. 2. When the load current exceeds a maximum current threshold, corresponding to the sense voltage threshold T_2 , the switching transistor 12 will be turned off resulting in a corresponding decrease or ramping down of the load current. This will continue until the load current falls below a minimum load current threshold corresponding to a lower voltage threshold T_1 shown in FIG. 2. When this occurs, the transistor 12 will again be switched on resulting in a repetition of the previously described cycle. The end result is that an average current through the inductive load 11 is maintained at a level between load current thresholds corresponding to the voltage thresholds T_2 and T_1 shown in FIG. 2. Many prior load driver circuits which control current in an inductive load operate generally as described above. However, prior load driver circuits were subject to erroneous operation because noise on a load current sense signal, such as the signal V_s , might result in unwanted switching or nonswitching of the transistor 12 such that a desired average load current would not be achieved. The load driver circuit described herein minimizes the chance of this occurring through the utilization of the circuitry which will now be described.

Referring again to FIG. 1, preferably the voltage sense signal V_s , which is indicative of the solenoid load current I_L , is provided as a differential input voltage signal to an integrated circuit (IC) 20 shown within dashed outline in FIG. 1. More specifically, the terminal 15 is coupled through a resistor R_1 to a positive input of a high side comparator C_1 and the terminal 17 is coupled through a resistor R_2 to a negative input of the comparator C_1 . An output of the comparator C_1 is provided at a terminal 21 and the comparator has a control input terminal 22 wherein for a high logic state at the terminal 22 the comparator is enabled or turned on and for a low logic state at this terminal the comparator is disabled or turned off. The resistors R_1 and R_2 also couple the sense voltage V_s to positive and negative inputs of a low side comparator C_2 which provides an output at a terminal 23 and has an input control terminal 24 which functions identically to input control terminal 22 of the comparator C_1 .

Each of the comparator output terminals 21 and 23 is connected to a five volt bias supply voltage V_{dd} through pull up resistors 25 and 26, respectively. The comparator output terminals 21 and 23 are connected, respectively, to not set and not reset inputs terminals $\bar{S}$ and R of a set-reset latch 27 which provides an output at a terminal 28 corresponding to the Q output terminal of the latch. The latch output terminal 28 is connected as an input to a time delay circuit 30 which provides a delayed output at a terminal 31. The terminal 31 is connected as an input to an AND gate 32 having its output connected to the terminal 24. The terminal 31 is also connected through an inverting stage 33 as an input to an AND gate 34 having its output connected to the terminal 22. The terminal 31 is also connected to a non-inverting control input terminal 35 of a series pass gate 36 connected between the negative input of the comparator C_1 and a threshold current generator 37. Similarly, the terminal 31 is connected to an inverting control input terminal 38 of a series pass gate 39 connected between the threshold current generator 37 and the positive input of the comparator C_1 . The negative sense terminal 17 is connected as an input to a comparator lockout/enable circuit 40 on the IC 20, and an output terminal 41 of the comparator lockout and enable circuit 40 is directly connected as an input to the AND gate 34 and is connected through an inverter stage 42 as an input to the AND gate 32. All of the above described components are preferably within the integrated circuit 20 as shown in FIG. 1.

The switching transistor 12 and the current sensing resistor 16 are not shown within the IC 20 since these are high power components and probably cannot be economically implemented in a single IC which contains the other electronics shown within the dashed outline 20 in FIG. 1. Besides the components discussed above, an AND gate 43 is provided such that the latch output terminal 28 is connected as an input thereto along with a terminal 44 at which a command input signal is provided. An output of the AND gate 43 is directly connected to the control terminal 18 corresponding to the gate electrode of the transistor 12. While the AND gate 43 is not shown within the integrated circuit 20, this component, or an equivalent of this component, could be readily provided within the integrated circuit 20.

It should be noted that preferably the low side comparator C_2 receives operating potential by virtue of a connection 45 between the comparator and the five volt bias supply potential V_{dd} . No such connection is shown for the comparator C_1 since operating potential for this comparator will preferably be provided by the connections of the positive and negative inputs of the comparator C_1 to the terminals 15 and 17. The comparator C_1 will be only rendered operative or enabled by the comparator lockout/enable circuit 40 when a sufficient potential exists at the terminals 15 and 17. Thus the comparator C_1 will only be enabled when the terminals 15 and 17 can provide sufficient operating potential to insure proper operating potential for the comparator C_1 . The detailed operation of the load driver circuit 10 will now be discussed.

The voltage sense signal V_s , which is indicative of the instantaneous magnitude of the load current I_L , is provided as a differential input to the integrated circuit 20. The circuit 20 causes the switching output transistor 12 to be repetitively turned on and off by repetitively switching it between conductive and nonconductive

states. During the conductive state of the transistor 12 the terminal 17 will be at substantially ground potential and substantially all of the load current I_L will pass through the sensing resistor 16 since the comparators C_1 and C_2 have high input impedances and the resistors R_1 and R_2 are substantially higher than the magnitude of the resistor 16 and the impedance from terminal 17 to ground when the transistor 12 is on. The result is that when the transistor 12 is turned on current through the solenoid coil 11 will start to increase and the magnitude of the sense voltage V_s will similarly increase. When the transistor 12 is turned off, the load current I_L will start to decrease but will continue in its same direction due to the action of the flyback or recirculation diode 19. This will result in a gradual decrease of the sense voltage V_s . These increases and decreases of the current sensing voltage V_s provide the current sense input to the integrated circuit 20 which will control the repetitive turning on and turning off of the transistor 12 so as to maintain a desired average current level in the solenoid coil 11 when such an average current is desired.

The signal at the command input terminal 44 will be high whenever a desired average current is to be provided for the solenoid coil 11. Thus, when it is desired to actuate the solenoid coil 11, a high signal is then provided at the terminal 44 by a command circuit not shown in FIG. 1. At the time the signal at terminal 44 initially goes high, there will be a high logic signal at the output terminal 28 of the latch 27. The reason for the initial high logic state at terminal 28 can be explained as follows.

Prior to generating a high signal at the terminal 44, the transistor 12 was off because the AND gate 43 was producing a low output state and that ensured the off condition of the transistor 12. When the transistor 12 is off and has been off for a substantial time, the load current I_L will have decayed to approximately zero and there will be essentially no voltage across the sense resistor 16. Note that FIG. 2 represents variations of the sense voltage V_s during a steady state repetitive switching condition for the transistor 12, which condition is implemented in response to the presence of a high logic signal at the terminal 44. Thus an initial approximately zero voltage condition of the voltage V_s is not shown in FIG. 2. However, for such an initial zero voltage for V_s , the comparator C_1 , since the differential voltage V_s will be far below the thresholds T_1 and T_2 , will provide a low logic state at its output terminal 21. This initial low logic state, also referred to herein as a set on signal, will result in setting the output of the latch 27 high at the terminal 28. In response to the high signal at the terminal 28, the time delay circuit 30 will implement a corresponding high signal at the terminal 31 at least five, and preferably thirty, nanoseconds later. When this delayed high logic state at the terminal 31 occurs, this will result in disabling the comparator C_1 because of the action of the inverting stage 33 and the AND gate 34 providing a low logic state at the terminal 22 to effectively turn-off (disable) the comparator C_1 . However, the output of the latch 27 will remain set high. This condition, in combination with the high command signal at 44 will turn on transistor 12.

The presence of a high logic state at the terminal 31 will also result in closing the series pass gate 36 and opening the series pass gate 39, whereas with a low logic state at the terminal 31 the opposite conditions existed. The threshold current generator 37 essentially provides two predetermined current levels I_1 and I_2

having polarities as indicated in FIG. 1. The series gates 36 and 39 selectively provide one or the other of these currents to establish the switching thresholds T_1 and T_2 in accordance with the following equations:

$$5 \quad T_1 = I_1(R_1) \quad 3 \quad T_2 = I_2(R_2)$$

From the above equations it is clear that the logic state at the terminal 31 determines which one of the thresholds will be implemented by virtue of enabling or disabling the gates 36 and 39 such that only one of the currents I_1 or I_2 will set a threshold for the comparators C_1 and C_2 . However, the signal at the terminal 31 will also determine, by virtue of the AND gates 32 and 34, which one of these comparators C_1 and C_2 will be disabled. The Comparators C_1 and C_2 , once disabled by one of the AND gates 32 or 34, will remain disabled until at least the next time occurrence of a low output by the nondisabled comparator. This is further explained in the following paragraphs.

When it is desired to actuate the solenoid 11, a high logic signal is provided at the terminal 44. As was explained above, a high logic signal is already provided at the terminal 28 when there has previously been no load current flowing in the solenoid coil 11. Therefore, the AND gate 43 will turn on the switching transistor 12 and cause current to increase in the load coil 11. During this time of current increase, high logic states are maintained at the terminals 28 and 31 because of the holding action of the latch 27. The high logic state at the terminal 31 ensures that the series gate 36 is enabled and that the series gate 39 is disabled. The logic state at the terminal 31 also ensures that the comparator C_1 is disabled due to the action of the inverter 33 and the AND gate 34. Thus only the comparator C_2 can be enabled during the increase of current caused by the turning on of the transistor 12.

The enabling of the comparator C_2 occurs in accordance with the output of the comparator lockout/enable circuit 40 which output is provided at the terminal 41. The comparator lockout/enable circuit 40 is actually just a comparator circuit in which the voltage at the terminal 17 is provided at a positive input of a comparator that receives at its negative input a predetermined, fixed 2.5 volt voltage. Thus, if the voltage at terminal 17 is less than 2.5 volts, the logic state or voltage level at the terminal 41 is low and this results in enabling the comparator C_2 if a high logic state is provided at terminal 31. If the voltage at the terminal 17 is higher than 2.5 volts, then a high logic state is provided at the terminal 41 and the comparator C_2 is disabled by the comparator lockout/enable circuit 40, via the inverter stage 42 and AND gate 32, if a high logic state is provided at terminal 31.

Prior to the transistor 12 being turned on after it has been off for an appreciable time, a high voltage ($B+$) is present at the terminal 17 resulting in the comparator lockout/enable circuit 40 disabling the comparator C_2 . However, when the transistor 12 is turned on, the voltage at the terminal 17 will be approximately ground potential and a low logic state is provided at the terminal 41 thus enabling the low side or C_2 . With comparator C_2 enabled, and the gate 36 enabled, the comparator C_2 proceeds with its function of comparing the sense voltage V_s with the predetermined maximum current threshold corresponding to the threshold T_2 . When this threshold is exceeded, the comparator C_2 will provide a low output, also referred to herein as a set off signal, at terminal 23 resulting in the resetting of the latch 27 such

that its output is now zero or a low logic state. This results in immediately turning off the transistor 12 due to the operation of the AND gate 43, and the load current I_L starts to decrease. This also results, after the nanosecond delay implemented by the delay circuit 30, in subsequently turning off (disabling) the comparator C_2 and permitting the comparator C_1 to now be enabled by action of the comparator lockout/enable circuit 40 due to the action of gates 32 and 34 and inverter 33. The circuit 40 will enable the comparator C_1 because the voltage at terminal 17 will rise, after transistor 12 goes off, toward the voltage $B+$. In addition to disabling the comparator C_2 , providing a low signal at the terminal 31 also disables the gate 36 and enables the gate 39 to establish the minimum current threshold corresponding to the threshold T_1 which threshold will be utilized by the comparator C_1 when it is enabled.

As the voltage at the terminal 17 rises when the transistor 12 is turned off, eventually this voltage will exceed 2.5 volts and the comparator lockout/enable circuit 40 will produce a high logic state at the terminal 41. This will result in enabling the comparator C_1 due to the action of the AND gate 34. With the comparator C_1 now enabled, when the sense voltage V_s goes below the threshold T_1 the comparator C_1 will now produce a low signal (set on signal) at its output terminal 21 resulting in setting the latch 27 to a high logic state and implementing the turning on of the transistor 12. This also results in the subsequent disabling of the comparator C_1 and the re-establishment of the threshold T_2 .

Essentially, the configuration shown in FIG. 1 implements the repetitive turning on and off of the transistor 12 when a command input signal high logic state is provided at the terminal 44. Two separate comparators C_1 and C_2 are utilized to essentially perform proper switching at maximum and minimum load current thresholds corresponding to the voltage thresholds T_2 and T_1 . However, the driver circuit 10 differs from prior load driver circuits in that once any of the comparators C_1 or C_2 produces an output signal indicative of the load current being above the maximum load current or below the minimum load current, then that comparator will be subsequently disabled, after a delay time, such that that comparator cannot produce subsequent additional output signals which might interfere with the operation of the load circuit 10. This disabling of one of the comparators will be maintained until the next time occurrence of an output (set on or set off signal) by the other one of the comparators C_1 or C_2 which is not disabled. Thus the comparators C_1 and C_2 alternately disable themselves. This minimizes the effect of noise on the operation of the circuit 10 since noise on the signal V_s cannot result in multiple set on signals by the comparator C_1 at terminal 21 or multiple set off signals by the comparator C_2 at terminal 23 because after the first set on or set off signal provided at the terminals 21 or 23 these comparators are disabled until the other comparator provides an output. In addition, the comparator lockout/enable circuit 40 ensures that the comparators C_1 and C_2 will only be enabled for providing an output at appropriate times. For example, it makes no sense to enable the low side comparator C_2 , whose output might result in turning the transistor 12 off, unless you are sure that the transistor 12 is already on. Thus the comparator lockout/enable circuit 40 ensures that the low side comparator C_2 will only be enabled if the voltage at the terminal 17 is below 2.5 volts. This will clearly occur when the transistor 12 is on. When the transistor 12 is

off and maintained in an off condition, the voltage at the terminal 17 will rise to $B+$ and therefore be above 2.5 volts. Under such a condition of course the comparator lockout/enable circuit 40 should not enable the comparator C_2 and allow this comparator to potentially generate additional set off signals at the terminal 23 since these set off signals would clearly have no beneficial effect because the transistor 12 was already off. Thus the present circuit 10 eliminates this possibility.

The action of the comparator lockout/enable circuit 40 with respect to the comparator C_1 is similar except that in that case it is even more significant that the comparator C_1 is only enabled if the voltages at the terminal 17 is above 2.5 volts. This is because the voltage at the terminals 15 and 17 actually provide some internal biasing voltage for the comparator C_1 as it is preferably implemented in IC form. Because of this, you certainly wouldn't want to enable the comparator C_1 if it was not receiving adequate bias voltage since you could not then rely on the output of the comparator. The comparator lockout/enable circuit 40 eliminates this problem as well as ensuring that the comparator C_1 will only be enabled if the transistor 12 is off.

Essentially, the comparator lockout/enable circuit 40 will enable the comparators C_1 and C_2 in response to comparing a sense voltage, such as the voltage at the terminal 17 which is indicative of the voltage at the drain electrode D of the switching device 12, with respect to a predetermined voltage level, which is preferably fixed at 2.5 volts in the present embodiment.

This assures that the comparators C_1 and C_2 will only be enabled when it is time for those comparators to provide an output, and this ensures that the comparator C_1 which depends upon the voltages at the terminals 15 and 17 for bias voltage, will only be enabled when a sufficient voltage exists at those terminals. In addition, the feedback path, which includes the delay circuit 30, provided between the terminal 28 and the control terminals 22 and 24 of the comparators C_1 and C_2 results in having each comparator turn itself off, disable itself, after it provides a low logic output. This disabling of the comparator will be maintained until the next time occurrence of a low level output by the other comparator. This ensures that once a comparator C_1 or C_2 has provided a low output it will not then subsequently generate multiple additional outputs of low logic states until the other one of the comparators C_1 and C_2 has produced a low output state. Thus any problems that may be associated with the comparators C_1 or C_2 providing undesired multiple low output signals have been eliminated.

It should be noted that when the term "disable" is used herein to describe the nonoperative condition of the comparators C_1 or C_2 , it refers to the turning off of the comparators such that they provide an open collector, open circuit, output regardless of the magnitude of the comparator input signals. Thus when a comparator is disabled it cannot provide a low set on signal or a low set off signal no matter what size noise signal may be present on the signal V_s . Thus the disabling of the comparators C_1 and C_2 contemplated herein is not similar to providing these comparators with hysteresis since hysteresis in a comparator can be overcome by an input voltage of sufficient magnitude.

It should be noted that the providing of the time delay circuit 30 is significant because its delay time permits the output of the latch 27 to stabilize without terminating the set or reset input that resulted in the

setting or resetting of the latch 27. In other words, without the time delay circuit 30, when the comparator C_1 , for example, sets the output of latch 27 high, if the comparator C_1 were immediately disabled, thus immediately removing the set input to the latch 27, this might result in the output of the latch 27 reverting to a low state. However, the time delay circuit 30 provides sufficient stabilization time for quieting of the output of the latch 27. The delay circuit 30 can comprise just a number of amplifying/inverting buffer stages connected in series.

FIG. 3 illustrates a typical simplified IC configuration for the comparators C_1 and C_2 wherein various bias voltage/current terminals V_s through V_{B7} are illustrated. The illustrated configuration for comparator C_1 indicates how this comparator uses voltages at terminals 15 and 17 for biasing rather than using the 5 volt V_{cc} bias voltage used for comparator C_2 . However, even without FIG. 3, the above description adequately explains the preferred operation of the load driver circuit 10. FIG. 3 also illustrates the preferred configuration for the comparator lockout/enable circuit 40.

While I have shown and described specific embodiments of this invention, further modifications and improvements will occur to those skilled in the art. All such modifications which retain the basic underlying principles disclosed and claimed herein are within the scope of this invention.

I claim:

1. Load driver circuit comprising:
first comparator means for receiving a load current signal indicative of current flowing through a load and for providing as an output signal a set on signal in response to said load current signal being less than a first threshold;
second comparator means for receiving said load current signal and providing as an output signal a set off signal in response to said load current exceeding a second threshold more than said first threshold;
driver means coupled to said first and second comparator means for receiving said set on signal and said set off signal and providing a load current control signal for controlling current flow through said load in response thereto;
wherein the improvement comprises means for disabling at least one of said first and second comparator means in response to and after said one of said first and second comparator means provides its output signal, whereby the generation of undesired set on/set off signals due to noise signals is minimized.
2. A load driver circuit according to claim 1 wherein said disabling means includes means for disabling each of said first and second comparator means in response to and after each of said first and second comparator means provides its output signal, respectively.
3. A load driver circuit according to claim 2 wherein said disabling means includes feedback means, which includes delay circuit means, for providing a time delay between the providing of said set on and set off signals and the resultant disabling of said first and second comparators means in response to said set on and set off signals.
4. A load driver circuit according to claim 3 wherein said time delay provided by said delay circuit means has a magnitude of at least five nanoseconds.

5. A load driver circuit according to claim 3 wherein said driver means comprises a latch means which receives said set on and set off signals and provides in response thereto an output signal at an output of said latch means for determining said load current control signal.

6. A load driver circuit according to claim 5 wherein said latch means output signal is alternately set to high and low logic states by said set on and set off signals.

10 7. A load driver circuit according to claim 6 wherein said driver means includes logic gate means for receiving said output signal of said latch means and a command signal as inputs and providing said current control signal as an output.

15 8. A load driver circuit according to claim 5 wherein said feedback means is coupled between said latch means output and said first and second comparator means.

9. A load driver circuit according to claim 2 wherein 20 said disabling means maintains each one of said first and second comparator means disabled until at least the next time occurrence of another of said first and second comparator means providing its output signal.

10. A load driver circuit according to claim 1 wherein 25 said disabling means maintains said one of said first and second comparator means disabled until at least the next time occurrence of another one of said first and second comparator means providing its output signal.

11. A load driver circuit according to claim 1 which 30 includes enabling means for enabling said one of said first and second comparator means after said one of said first and second comparator means has been disabled by said disabling means.

12. Load driver circuit comprising:
first comparator means for receiving a load current signal indicative of current flowing through a load and for providing as an output signal a set on signal in response to said load current signal being less than a first threshold;

second comparator means for receiving said load current signal and providing as an output signal a set off signal in response to said load current exceeding a second threshold more than said first threshold;

driver means coupled to said first and second comparator means for receiving said set on signal and said set off signal and providing a load current control signal for controlling current flow through said load in response thereto, said driver means including an output switching device having a control terminal, which control terminal receives said control signal, and said output switching device having a pair of output terminals, at least one of said output terminals to be coupled to said load; wherein the improvement comprises means for enabling at least one of said first and second comparator means in response to comparing a sensed voltage, indicative of the voltage at said one output terminal of said device, with respect to a predetermined voltage.

13. A load driver circuit according to claim 12 wherein said enabling means includes means for enabling one of said first and second comparator means in response to said sensed voltage exceeding said predetermined voltage and otherwise enabling a different one of said first and second comparator means.

14. A load driver circuit according to claim 12 wherein said enabling means comprises a third compar-

ator means having one input coupled to said one output terminal of said device.

15. A load driver circuit according to claim 12 wherein said enabling means alternately and repetitively enables one of said first and second comparator means and then another one of said first and second comparator means in response to variations of said sensed voltage provided in response to said set off and set on signals. 5

16. A load driver circuit according to claim 12 which includes means for disabling at least one of said first and second comparator means in response to and after said one of said first and second comparator means provides its output signal, and wherein said disabling means maintains said one of said first and second comparator means disabled until at least the next time occurrence of another one of said first and second comparator means providing its output signal. 10 15

17. A load driver circuit according to claim 16 wherein said disabling means also includes means for disabling said another one of said first and second comparator means in response to and after said another one of said first and second comparator means provides its output signal and wherein said disabling means maintains said another one of said first and second comparator means disabled until at least the next time occurrence of said one of said first and second comparator means providing its output signal. 20 25

18. Load driver circuit comprising:
a load having a varying load current therein;
an output switching device having a control input terminal and a pair of output terminals, at least one of said output terminals coupled to said load and said control input terminal receiving a current control signal for controlling said load current in said load;
first comparator means for receiving a load current signal indicative of said load current flowing 30 35

through said load and for providing as an output signal a set on signal in response to said load current signal being less than a first threshold; second comparator means for receiving said load current signal and providing as an output signal a set off signal in response to said load current exceeding a second threshold more than said first threshold;

driver means, which includes said output switching device, coupled to said first and second comparator means for receiving said set on signal and said set off signal and providing said load current control signal in response thereto;

means for disabling one of said first and second comparator means in response to and after said one of said first and second comparator means provides its output signal; and

means for enabling said one of said first and second comparator means in response to comparing a sensed voltage, indicative of the voltage at said one output terminal of said switching device, with respect to a predetermined voltage.

19. A load driver circuit according to claim 18 wherein said disabling means includes means for disabling each of said first and second comparator means in response to and after each of said first and second comparator means provides its output signal, respectively, and wherein said enabling means enables each of said first and second comparator means in response to the comparison of said sensed voltage after the disabling of each of said first and second comparator means by said disabling means. 30 35

20. A load driver circuit according to claim 19 which includes a load current sensing resistor connected in series with said load, said load current signal being provided across said load current sensing resistor.
